UNITED STATES PATENT OFFICE.

MILTON R. HUNTER, OF CINCINNATI, OHIO, ASSIGNOR OF ONE-HALF TO
HENRY A. PERKINS, OF SAME PLACE.

RIDING-SADDLE.

SPECIFICATION forming part of Letters Patent No. 242,650, dated June 7, 1881.

Application filed April 11, 1881. (No model.)

To all whom it may concern:

Be it known that I, MILTON R. HUNTER, of Cincinnati, Hamilton county, Ohio, have invented a new and useful Improvement in Riding-Saddles, of which the following is a specification.

My invention relates to an improved metallic coupler or plate for uniting together the gullet and stay-strap of a riding-saddle, said plate having an eye for engagement of the lacing-strap or girth-plate.

In the accompanying drawings, Figure 1 is a perspective view of a riding-saddle furnished with my improved coupler. Fig. 2 is a top view, and Fig. 3 a section on the line *xx* of my coupler.

A may represent a saddle of any desired form.

B is my improved coupler or eye-plate, which plate consists of an annular middle portion or ring, *b*, from which radiate two tags or lugs, *b' b''*, whose faces are somewhat depressed below the level of the ring, which is cut away at their point of junction, so as to present square shoulders *b'''*. Each tag is perforated, as at *b^{iv}*, to receive rivets *C*, which unite the coupler to the gullet *D* and the stay-strap *E*. The

depression of the faces of the tags is such as to cause the faces of the said gullet and stay-strap to be flush with the ring-face, so as to 30 present smooth surfaces for contact with the legs of the rider.

To the ring *B* the lacing-plate or girth *F* is secured by looping and riveting, as shown in Fig. 1.

Instead of one hole and rivet, two or more may be used in each tag where extraordinary strength is desired.

I claim as new and of my invention—

1. The eye-plate *B*, formed with middle ring 40 portion, *b*, and the depressed and perforated radial lugs, *b' b''*, in combination with gullet *D*, stay-strap *E*, lacing-plate or girth *F*, and riding-saddle *A*, as set forth.

2. As a new article of manufacture, the coupler or eye-plate having an annular middle portion or ring, two tags or lugs, square shoulders, and perforations, as set forth.

In testimony of which invention I hereunto set my hand.

MILTON R. HUNTER.
